DEVICE FOR THE CONTROL OR MEASUREMENT OF THE FLOW OF THE CONTENTS FROM CARTONS OR CONTAINERS

Albert L. Nelsen, Fargo, N. Dak.

Application April 5, 1937, Serial No. 135,117

6 Claims. (Cl. 221—98)

This invention relates to a measuring dispenser, and it is primarily an object of the invention to provide a device or structure of this kind which, as a result of conventional tipping or overturning 5 manipulations of the carton or container, permits the discharge of the contents of the carton or container in predetermined bulk or desired quantity.

It is also an object of the invention to provide 10 a measuring dispenser which provides for the discharge in predetermined bulk or desired quantity the contents of a carton or container when such carton or container is in a certain position or adjustment permitting the discharge of 15 a lesser quantity.

The invention also has for an object to provide 20 a measuring dispenser wherein the salient features are housed within the carton or container and wherein the structure is such as to eliminate the use of any mechanically operated parts.

The invention consists in the details of construction and in the combination and arrangement of the several parts of my improved measuring dispenser whereby certain important advantages are attained and the device rendered 25 simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:—

Figure 1 is a view in plan of a blank from which is produced a container having a measuring dispenser constructed in accordance with an embodiment of my invention;

Figure 2 is a vertical sectional view taken 40 through an assembled container and measuring dispenser constructed from the blank as illustrated in Figure 1;

Figure 3 is a view in plan of a blank illustrating 45 a measuring dispenser constructed in accordance with another embodiment of my invention;

Figure 4 is a fragmentary view partly in section and partly in elevation illustrating a container having arranged therein a measuring dispenser produced from a blank such as illustrated in Figure 3;

Figures 5 to 11 inclusive are diagrammatic views illustrating in sequence the steps of discharging the contents of a container including a measuring dispenser in accordance with either of 50 the two embodiments of invention as herein dis-

closed together with the steps after discharge for refilling the measuring dispenser for a subsequent delivery.

In the embodiment of my invention as illustrated in Figures 1 and 2, the measuring dispenser 5 is a part of the carton or container and the measuring dispenser proper is comprised in the one blank from which the container and measuring dispenser are produced as a unit.

As illustrated in Figure 1, A denotes what may 10 be termed the front wall or panel of the carton or container and B a rear wall. Interposed between the walls or faces A and B and separated therefrom by the score lines 1 is a side wall S and separated from the wall A by the score line 2 is a 15 second side wall W. The outer marginal portion of this side wall W is continued therealong with a relatively short tab 3 separated from the side wall W by the score line 4 parallel with the score line 2 hereinbefore referred to. Separated from the wall W by the score lines 5 extending transversely thereof are the end panels E. The score lines 5 are continued by the score lines 6 extending transversely across the side wall S and these score lines 6 in turn are continued by the score 20 lines 7 extending transversely across the wall B. The score lines 7 separate from the wall B the 25 end flaps F.

The score lines 6 separate from the side wall S the end tabs 8 and 9. The side marginal portion of the tab 9 is cut on the lines 10 to provide a tab 11 at the inner end of the adjacent flap F and which tab 11 is separated from the flap F by a core line 12 extending transversely of the flap F. The tab 9 is extended by the tab 14 35 of desired length but of a width substantially equal to the width of the side wall S. The longitudinal margins of the tab 14 are separated by the score lines 15 from the flaps 16. These flaps 16 in plan are substantially V-shaped in form 40 with their apices outwardly disposed. These flaps 16 also extend entirely along the flap 14 with the inner inclined edges 17 terminating at the junction of the score lines 15 and the score line 18 separating the tabs 9 and 14. The outer 45 inclined edges 19 of the flaps 16 terminate at desired points outwardly and laterally from the score lines 15 whereby the flaps 16 at their outer ends are provided with relatively short edges 20, the length of which determining the width of the 50 receiving opening for the dispensing structure as will hereinafter appear.

The score lines 5 are also continued by the score lines 21 which extend across the side wall W and separate the same from the tabs 22 and 23. The 55

outer portion of the tab 23 is separated by the transversely disposed score line 24 from an end flap 25, and the extremities of the flap 25 are separated by the transversely disposed score lines 26 from the outstanding wings 27 aligned with each other and with the flap 25.

The tabs 8 and 22 are of substantially the same length and the combined lengths of the tab 23 and flap 25 are substantially equal to the combined lengths of the tabs 9 and 14.

In producing a container and measuring dispenser from the blank as illustrated in Figure 1, the tab 9 is folded on the line 6 to overlie the inner face of the wall S and the tab 14 is folded upwardly on the line 18 and the flaps 16 folded inwardly on the lines 16 in a direction toward the wall S. The flaps 16 are adjusted with their apices registering with the junctions of the score lines 1 and 5 and 1 and 7 whereupon the walls 20 A and B are swung one toward the other along the lines 1. The flaps 16 are then adhesively secured to the inner faces of the walls A and B. To provide for this securement the proper faces of the flaps 16 have disposed thereover a lamination 25 of glue or other adhesive material or, if preferred, the desired adhesive or cementitious material may be applied to the flaps 16 at the time of assembly.

The side wall W is then properly folded on the line 2 so that the flap 3 may be adhesively or otherwise secured to the opposed faces of the walls S and W. The straight edges 20 of the flaps 16 provide an entrance opening for the contents of the completed container within the dispensing device as is more particularly illustrated in Figure 35.2. The tab 23 is then folded inwardly between the spaced walls S and W until this tab 23 assumes a position substantially flush with the adjacent ends of the walls A and B as determined by the score lines 5 and 7. The flap 25 is then flexed inwardly on the line 24 substantially at right angles to the tab 23 and the wings 27 are folded on the lines 26 to extend forwardly of and substantially at right angles to the flap 25 and adhesively or otherwise secured to the adjacent corner faces of the walls A and B. By this means is provided a discharge spout closely adjacent to the side wall S. The tab F is then folded inwardly into closed position on the score line 7 and the flap 11 folded downwardly on the score line 12 for adhesive connection to an adjacent portion of the wall S. The flap E is then folded on the line 5 over the folded flap F and adhesively or otherwise secured thereto. The flap 11 indicates the portion of the closed end which is to be lifted into open position to permit discharge of material out through the discharge spout. The flaps E and F at the end portions of the walls A and B remote from the measuring dispenser structure are folded on their respective lines 5, 6, 7 and 21 to close said end of the box.

Figures 5 to 11 inclusive illustrate the various successive steps in discharging the contents from within the container C. These figures are diagrammatic in character and the discharge spout is indicated at a and the measuring pocket at b. In Figure 5 the container is in an upright position with a predetermined quantity of the contents of the container C in the pocket b. As the container C is tipped over, as shown in Figure 6, to the horizontal position as illustrated in Figure 7, no discharge of the contents is obtained but as the container is moved to an inverted inclined position as illustrated in Figure 8 the contents of the container within the measuring pocket will 75 discharge out through the spout a. This pouring

action will continue until the container C assumes a substantially vertical inverted position as illustrated in Figure 9. At this time the content of the container drops to the then bottom portion of the container but will not continue to flow out through the spout a. However, as the container C is again moved into substantially a horizontal position as illustrated in Figure 10 and then returned to its vertical position as indicated in Figure 11, the measuring pocket b will be refilled. It 10 is believed to be obvious that just so long as there is any material within the container C a supply can be delivered within the measuring pocket b.

It is to be stated, however, that with the container C in the horizontal position as illustrated 15 in both Figures 7 and 10, a small amount of the contents may be discharged by slightly shaking the carton.

In the embodiment of the invention as illustrated in Figures 3 and 4, the measuring dispenser is constructed as a separate unit but is positioned within the carton to function in the same manner as the measuring dispenser comprised in the first embodiment of my invention. In the structure as illustrated in Figures 3 and 4 20 25 the measuring dispenser comprises an elongated narrow sheet of material having extending transversely thereacross at approximately its longitudinal center a score line 28 whereby is provided two walls 30 and 31. The wall 30 is separated by the longitudinally disposed score lines 32 from the substantially V-shaped flaps 33 of a configuration substantially the same as the form of the flaps 16 hereinbefore referred to.

The wall 31 at one side thereof is provided with 35 a flap 34 separated from the wall 31 by the score line 35. The inner portion of the wall 31 at the opposite side thereof is provided with the relatively small flap 36 separated from the wall 31 by the score line 37. This score line 37 extends 40 to the outer end of the wall 31 and the outer portion of such score line separates from the wall 31 the relatively narrow side wall 38 which is continued by a spout wall 39 separated from the side wall 38 by a score line 40. This spout wall 39 is 45 of a width substantially the same as the width of the wall 31 and the outer or free end portion of the wall 39 is continued by a flap 41 separated from the wall 39 by a score line 42. The upper or top marginal portion of the wall 39 is continued 50 by a hood wall 43 separated from the spout wall 39 by the score line 44. Extending outwardly from the sides of the hood wall 43 are the flaps 45 separated from the hood wall 43 by the score lines 46.

In assembling the measuring dispenser as illustrated in blank in Figure 3, the wall 38 is folded on the score line 37 to a position substantially at right angles to the wall 31 and the spout wall 39 is folded on the line 40 to extend transversely of the wall 31 and the flap 41 is folded on the line 42 substantially at right angles to the wall 39 and adhesively secured to the upper or outer portion of the flap 34 whereby a desired discharge spout is provided. It is, however, to be understood that the flap 34 is suitably folded on the line 35 and the flap 36 suitably folded on the line 37 to permit such flaps to be adhesively secured to the side walls 47 of the carton or container in which the measuring dispenser is 70 placed.

The wall 30 is folded on its line 28 on a required upward incline and the flaps 33 are also adhesively secured to the side walls 47 of the container or carton whereby this wall 30 is main- 75

tained in desired position with respect to the spout to provide a pocket to initially receive the material or contents to be discharged from the container or carton in substantially the same manner as has been hereinbefore described in detail in connection with the first embodiment of the invention.

The measuring dispenser constructed in accordance with this second embodiment of my invention is placed preferably against the end wall 48 of the carton or container immediately adjacent to an end thereof so that initially the discharge flow out through the spout is prevented by the conventional lid or top flaps 49. The wall 15 43 is folded on the line 44 so that said wall may have close contact from within with the lid or closing flaps 48 with the flaps 45 folded on the lines 46 to have close contact with the inner faces of the side walls 47 to provide means for sealing 20 against escape the contents of the container or carton between the applied measuring dispenser and carton. These flaps 45 may also be adhesively secured to the side walls 47.

It is to be noted that the inner edges 50 of the flaps 45 are on such bevel as to have close or butting contact with the straight edges 51 at the outer ends of the flaps 33 and which straight edges by their length determine the width of the entrance to the pocket of the measuring dispenser.

It is believed to be obvious that when it is desired to empty the contents of the carton or container that portion of the closing flaps or lid over the spout is suitably raised.

From the foregoing description it is thought to be obvious that a measuring dispenser constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as herein-after claimed.

I claim:—

50 1. A measuring dispenser adapted to be housed within a container adjacent to an end corner thereof comprising two walls, one of said walls being for attachment to a wall of the container and the other wall being upwardly and inwardly inclined to provide a receiving pocket, side flaps carried by the second wall, each of said side flaps being substantially in the form of a V with its apex outwardly disposed, each of said flaps extending entirely along its wall with the outer 55 end of the flap terminating in a straight edge, substantially at right angles to the wall, said side flaps being disposed toward the first wall and adapted for securement to adjacent walls of the container, the length of the straight edges of the flaps determining the width of the entrance to the pocket, and a strip bridging the space between the flaps at the upper portion thereof at points spaced from the first wall to provide a discharge spout.

70 2. A measuring dispenser adapted to be housed within a container adjacent to an end corner thereof comprising two walls, one of said walls being for attachment to a wall of the container and the other wall being upwardly and inwardly inclined to provide a receiving pocket, side flaps

carried by the second wall, each of said side flaps being substantially in the form of a V with its apex outwardly disposed, each of said flaps extending entirely along its wall with the outer end of the flap terminating in a straight edge substantially at right angles to the wall, said side flaps being disposed toward the first wall and adapted for securement to adjacent walls of the container, the length of the straight edges of the flaps determining the width of the entrance to the pocket, and a strip bridging the space between the flaps at the upper portion thereof at points spaced from the first wall to provide a discharge spout, said discharge spout extending within the pocket to a point below the entrance to the pocket.

3. A container having front and back walls, side walls and end walls, a tab carried by the extremity of one of the side walls and folded to overlie said side wall, said tab being continued by a second tab folded to extend inwardly and outwardly with respect to the container, said second tab being provided therealong with side flaps substantially V-shaped in form with their apices outwardly disposed, the inner edges of the flaps determining the angle of inclination of the second tab, the outer ends of the flaps having straight edges substantially at right angles to the second tab, the outer inclined edges of the flaps being substantially flush with the adjacent end of the container, the straight edges of the flaps determining the width of the entrance to the pocket provided by the folded tabs and flaps, a tab carried by an extremity of the second side wall and of a length to extend along the adjacent end of the container and partially overlie the top of the pocket, and a flap carried by the extremity of the last named tab above the pocket and extending within the pocket, said last named flap coacting with the first mentioned tab to provide a discharge spout.

4. A container having front and back walls, side walls and end walls, a tab carried by the extremity of one of the side walls and folded to overlie said side wall, said tab being continued by a second tab folded to extend inwardly and outwardly with respect to the container, said second tab being provided therealong with side flaps substantially V-shaped in form with their apices outwardly disposed, the inner edges of the flaps determining the angle of inclination of the second tab, the outer ends of the flaps having straight edges substantially at right angles to the second tab, the outer inclined edges of the flaps being substantially flush with the adjacent end of the container, the straight edges of the flaps determining the width of the entrance of the pocket provided by the folded tabs and flaps, a tab carried by an extremity of the second side wall and of a length to extend along the adjacent end of the container and partially overlie the top of the pocket, a flap carried by the extremity of the last named tab above the pocket and extending within the pocket, said last named flap coacting with the first mentioned tab to provide a discharge spout, and means carried by the last named flap for securing the same to the first named flap.

5. A measuring dispenser for placement within a container comprising two walls, one of said walls being inwardly and outwardly inclined with respect to the other walls, the side margins of the inclined wall having disposed therealong substantially V-shaped flaps at right angles to the wall, the apices of the flaps being outwardly

disposed and the outer ends of the flaps having straight edges at right angles to the wall, securing means carried by the marginal portions of the second wall, a side flap carried by the outer portion of the second wall at one side thereof, a strip connected at one end to said last named flap and disposed transversely across the adjacent outer end portion of the second wall, and an attaching means carried by the outer end portion of said cross strip, said cross strip coacting with the second named wall to provide a discharge spout.

6. A measuring dispenser for placement within a container comprising two walls, one of said walls being inwardly and outwardly inclined with respect to the other wall, the side margins of the inclined wall having disposed therealong substantially V-shaped flaps at right angles to the wall, the apices of the flaps being outwardly dis-

posed and the outer ends of the flaps having straight edges at right angles to the wall, securing means carried by the marginal portions of the second wall, a side flap carried by the outer portion of the second wall at one side thereof, a strip connected at one end to said last named flap and disposed transversely across the adjacent outer end portion of the second wall, an attaching means carried by the outer end portion of said cross strip, said cross strip coacting with the second named wall to provide a discharge spout, and a hood wall carried by the outer longitudinal margin of the cross strip to engage an applied closure for the container, said hood wall having end flaps to engage the side walls of the container in which the measuring dispenser is placed.

ALBERT L. NELSEN.
